MOLDED SEAT SHELL

Robert W. Schier, Northfield, and Leonard D. Singer, Chicago, Ill., assignors to Krueger Metal Products, Inc., Green Bay, Wis., a corporation of Wisconsin

Filed Mar. 18, 1968, Ser. No. 11,022

Term of patent 14 years

Int. Cl. D6—01

U.S. Cl. D15—8

FIG. 1 is a front three-quarter view in perspective of a seat shell embodying our design.

FIG. 2 is a rear three-quarter perspective view thereof.

FIG. 3 is a front elevational view thereof.

FIG. 4 is a side elevational view thereof.

FIG. 5 is a view taken in section on line 5—5 of FIG. 4.

FIG. 6 is a plan view of the seat shell.

FIG. 7 is a view taken in section on the line 7—7 of FIG. 3.

We claim:

The ornamental design for a molded seat shell, as shown.
